CLAIM

The ornamental design for a toddler fork, as shown and described herein.

DESCRIPTION

More than one reissue application has been filed for the reissue of U.S. Pat. No. D. 799,910. U.S. application Ser. No. 29/729,403, filed Mar. 26, 2020 and U.S. application Ser. No. 29/729,409, filed Mar. 26, 2020 were filed as divisional reissue applications from reissue U.S. application Ser. No. 29/704,367.

FIG. 1 illustrates a side view of a toddler fork showing my new design, the opposite side view being a mirror image thereof.

FIG. 2 illustrates a top plan view of the toddler fork of FIG. 1.

FIG. 3 illustrates a bottom plan view of the toddler fork of FIG. 1.

FIG. 4 illustrates a front elevational view of the toddler fork of FIG. 1.

FIG. 5 illustrates a perspective view of the top-side of the toddler fork of FIG. 1; and,

FIG. 6 illustrates a perspective view of the bottom-side of the toddler fork of FIG. 1.

Any broken lines in the drawings are for illustrative purposes only and form no part of the claimed design. Additionally, the toddler fork is not limited to the scale shown herein.

1 Claim, 6 Drawing Sheets

Matter enclosed in heavy brackets [ ] appears in the original patent but forms no part of this reissue; matter printed in italics indicates the additions made by reissue.
